(57) **CLAIM**

The ornamental design for a satellite dish cover, as shown and described.

DESCRIPTION

FIG. 1 is a perspective view of the satellite dish cover;
FIG. 2 is a side elevation, the opposite side being a mirror image thereof;
FIG. 3 is a front end elevation;
FIG. 4 is a rear end elevation;
FIG. 5 is a top plan view; and,
FIG. 6 is a bottom plan view.

The broken line showing of the support in FIG. 1 is for illustrative purposes only and for no part of the claimed design. The broken lines in FIG. 4 represent stitching.
